UNITED STATES PATENT OFFICE.

ARTHUR D. SMITH, OF ARKANSAS CITY, KANSAS.

APPARATUS FOR DISTILLING PETROLEUM-OILS.

1,374,402.

Specification of Letters Patent. Patented Apr. 12, 1921.

Application filed March 13, 1917. Serial No. 154,469.

To all whom it may concern:

Be it known that I, ARTHUR D. SMITH, a citizen of the United States, and a resident of Arkansas City, in the county of Cowley 5 and State of Kansas, have invented a new and useful Improvement in Apparatus for Distilling Petroleum-Oils, of which the following is a specification.

My invention relates to an improved form 10 of still particularly adapted to be used where heavy paraffin oil, fuel oil, or gas oil is distilled under a pressure ranging from about one hundred and twenty-five (125) pounds to one hundred and fifty (150) 15 pounds, and at a temperature ranging from about six hundred (600) degrees to seven hundred (700) degrees Fahrenheit. The object of the invention is to provide means for maintaining rapid cyclic circulation of 20 the oil throughout the system, with a view to effecting conversion of the charge into lighter hydrocarbons of the paraffin series, such as naphtha or gasolene, as set forth in my Patent No. 1,239,423, dated September 25 4, 1917, for a process of making gasolene, of which the present is a continuation in part.

In the practice of the process to which this invention relates, the oil is vaporized in 30 a closed system of connecting channels while being rapidly circulated throughout the system, the suspended carbon in the charge is removed by mechanical filtration of portions thereof, and the filtered oil is returned to the 35 system, together with as much fresh oil as is required, for maintaining the operation of the still continuously. One feature of my invention consists in sloping the main shell portion of the still as well as the tubular portion in order the more readily to effect 40 circulation and prevent any deposit of carbon within the still. A further feature is the mechanical means provided for aiding circulation and preventing any deposit 45 of carbon. Other features of the invention appear in connection with the description of the apparatus hereinafter described.

In order that my invention may be more 50 clearly understood, I will describe it embodied in a suitable form of apparatus, which I have found in practice to operate satisfactorily, reference being had to the accompanying drawing, which illustrates a 55 preferred form of the invention.

What I claim as my invention is set forth in the appended claims.

In the drawings, wherein the same reference characters are used to designate the same parts in the several views, 60

Figure 1 is a side elevation of the apparatus, showing it diagrammatically;

Fig. 2 is a vertical transverse cross-section of the still, on the line 2—2 in Fig. 1, looking in the direction of the arrows; and 65

Fig. 3 is an enlarged vertical transverse cross-section of the lower portion of the main shell of the still, on the line 3—3 looking in the direction of the arrows.

Referring now particularly to Fig. 1 of 70 the drawings, the apparatus comprises a furnace 1 of ordinary construction with customary fire door 2, ash pit door 3, ash pit 4, fire grate 5, up flue passage 6, down flue passage 7, and final up take 8 to stack 9. 75 Suspended from a gallows frame 10 by U bolts 11 is the main shell 12 of the still, which is of conical section, and is arranged with its axis horizontal so that its bottom slopes down toward the rear end. Beneath 80 the shell 12 are the downwardly and rearwardly inclined connecting tubes 13 which are joined to the ends of the main shell by the headers 14. The large conical end of the still is provided with an inclined vapor outlet line 15, which leads to the condenser.

The bottom of the rear header 14 is provided with a filter well 16, connecting to filter 17 through flow pipes 18, which are provided with valve 19 for controlling intermittent filtration. The filter is provided 90 with perforated false bottom plates 20 of heat resisting metal for supporting suitable filtering media 21, and have man plates 22 for cleaning them. Filtered oil is taken 95 from the bottom of the filter 17 through suction line 23 controlled by valve 24 to a rotary pump 25. The latter is of ordinary type excepting that it is furnished with oil cooled bearings 26 of special design. Oil 100 is returned to the system through a vertical pipe 27 which discharges into the front end of the shell of the still through a horizontal pipe 28. Additional fresh oil may be pumped into the system from storage tanks 105 29 through a suction pipe 30 controlled by a valve 31. Also additional filters 17 may be connected to the flow pipes 18 by suitable by-pass valves if desired.

Within the still a series of steel brushes 110

32 are arranged to rotate, so as to produce positive cyclic circulation of the charge in the still along its bottom from front to rear, part of the charge returning through the tubes 13 and part flowing back in the shell over the brushes. The brushes are arranged on parallel shafts 33, which are connected by driving chains 34. One of the shafts 33 projects through an oil cooled stuffing box 35 and has a sprocket wheel 36 on its outer end which is rotated from any suitable source of power, such as the motor driven line shaft 37. The shaft 33 is cooled by oil which is circulated through a system of ducts 38 drilled in it from a box 39 on its end. The stuffing boxes 35 and 39 are of similar design to that employed in the pump 25, and each has a chamber 40 surrounding the rotating shaft through which cool oil is caused to circulate by a suitable pump 41 and oil circulating pipes 42 and 43.

Within the upper part of the main shell 12 of the still is a coiled pipe 44 or series of radiating tubes provided with an inlet pipe 45 and an outlet pipe 46 for circulating oil through the vapor space in the still. The outlet pipe has two branches, controlled by valves 47, one of which branches leads to a cooling coil 48 and the other leads 25 to a heating coil 49. A pump 50 is provided for circulating oil through the radiating pipe or tubes 44 and through either the cooling coil 48 or the heating coil 49. The pump 50 is provided with oil cooled stuffing boxes and is driven from the line shaft 37 like the pump 25. An automatic expansion valve 51 is provided to relieve excess pressure in the coil 44. This valve discharges through a pipe which connects to 30 the suction line 30. A branch of the suction line 30 leads to the suction side of the pump 50 to fill the coil 44 as needed by opening the valve 52.

The stuffing boxes and bearings for the pumps 25 and 50 are cooled by oil circulated through the pipes 53 and 54 by the pump 41. A cooling coil 55 is provided for cooling the circulating oil, and control valves 56 permit the flow of cooling oil to 45 the various stuffing boxes to be properly adjusted. A relief valve 57 and a suction valve 58 are provided in the outlet and inlet pipes for the pump 41, which communicate with the storage tank 29 through branches 50 of the suction pipe 30. Two recording thermometers 59 are provided for controlling the operation of the still, one entering the still below the normal liquid level (indicated by the line 67 in Fig. 1), the other 55 entering the still in what is normally gaseous space. The sill is also provided with a recording pressure gage 60 and mannecks 61.

The operation of the apparatus described

above is as follows: The still is first filled 65 with heavy hydrocarbon oil and is heated to a temperature of approximately six hundred (600) to seven hundred (700) degrees Fahrenheit. The air is expelled and the pressure allowed to reach one hundred and twenty-five (125) to one hundred and fifty (150) pounds. The vapor which passes off through the pipe 15 is condensed in the coiled portion 62 in the water tank 63 and is released as liquid condensate into a receiving tank 64. The waste water from the tank 63 flows through the spray 65 and drips over the cooling coils 48 and 55. Pressure and temperature are regulated by suitable manipulation of the fire in the 70 grate and the release valve 66 on the receiving tank; also by circulating hot or cold oil through the vapor temperature controlling tubes 44 as may be desired. The positive 75 circulating system in the still, consisting of the brushes 32, is then started and maintained throughout the entire period of operation. Every four to five hours, or as occasion may require, the entire charge is drawn through the filters 17 alternating 80 from one to another by proper manipulation of the control valves, as may be required for cleaning out the filters; and at suitable intervals fresh oil is introduced 85 into the system through the suction valve 90 31 for rendering the operation of the apparatus continuous. The volume of oil in the still is determined by the difference in temperature as denoted by the control thermometers 59 which are immersed in the 100 liquid and gaseous levels, respectively, the gaseous portion of the still charge always being from one hundred (100) to one hundred and fifty (150) degrees lower in temperature than the liquid portion. Cold oil 105 supplied by the cooling pump 41 is constantly forced to the oil cooled bearings of the circulatory system throughout the operation of the still, and also to the bearings of the vapor temperature control pump if the 110 latter is pumping hot oil, in order to prevent the packing from burning out and stopping the operation of the still.

I have heretofore discovered that the sloping bottom of the still increases the tendency 115 toward circulation and diminishes carbon deposition, and I have further discovered that the conical shape of the main shell allows the vapor to rise more quickly to a portion of the still which can be kept comparatively cool with aid of the vapor temperature control coils, thereby preventing overheating of the vapor beyond four hundred and fifty (450) degrees Fahrenheit, which effects an increased yield of 120 permanent light hydrocarbons.

It is evident that changes in the shape and arrangement of the parts of the apparatus

may be made, and that the operation of the process may be modified within wide limits with the same apparatus.

What I claim as new and desire to secure 5 by Letters Patent is:

1. A still for treating petroleum oils comprising a main shell having a sloping bottom and sloping tubular portions connected to said shell at their ends and exposed to heat, 10 so as to induce a cyclic circulation through said tubes and shell, and a well below and communicating with the lower end of said shell, said sloping bottom lessening carbon deposition by promoting continuous movement 15 of the heavier parts of the still charge.

2. The combination of a still for treating petroleum oils comprising a shell portion and a tubular portion provided with sloping surfaces, a temperature control coil in the 20 vapor space of said shell, together with a mechanical circulating device in the bottom of said shell to produce circulation of the still contents, thereby preventing overheating and carbon deposition.

3. In combination, in an apparatus of the character described, a still having a downwardly sloping lower surface, a system of closed ducts connecting the lower end of said surface with its upper end, said system 30 of ducts being exposed to the action of heat, and means within said still for circulating its fluid and semi-fluid contents toward the lower end of said surface, and a well below and communicating with the lower end of 35 said shell.

4. In combination, in an apparatus of the character described, a still having a downwardly sloping lower surface, a system of closed ducts connecting the lower end of 40 said surface with its upper end, said system of ducts sloping oppositely to the slope of said lower surface and being exposed to the action of heat, means located at the lowermost point of said system for drawing off 45 portions of the contents thereof and removing the carbon therefrom, means for returning said portions to the still, and means within said still for circulating its fluid and semi-fluid contents toward the lower end of 50 said surface.

5. The combination with a petroleum still having means for continuously mechanically

propelling its liquid charge to effect rapid cyclic circulation thereof of a mechanical filtering device and an external circuit leading 55 from the lower portion of the still system through such filtering device and back to the still, whereby suspended carbon may be removed intermittently and the carbon free oil returned to the system. 60

6. The combination of a petroleum distillation still having a sloping bottom arranged for cyclic circulation within it, an external circuit arranged to receive oil from said still and return it thereto, a filtering device 65 and means operable at will for connecting said filtering device in said external circuit, and an external source of supply of oil, whereby suspended carbon may be removed intermittently and the carbon free oil 70 returned to the system together with as much fresh oil as is necessary to make the process continuous.

7. The combination with a petroleum still of a plurality of thermometer devices exposed 75 at different levels therein, one of said devices being exposed in the vapor space in the upper part of the still and another being exposed at such elevation in said still as to be covered by the normal 80 liquid charge and be uncovered whenever the charge falls a comparatively small distance below its normal level, whereby the difference in temperature between the liquid and gaseous media indicates whether or not 85 the charge needs replenishing.

8. The combination with a petroleum still having a temperature control coil in the vapor space thereof of a plurality of thermometer devices exposed at different levels 90 therein, one of said devices being exposed in the vapor space in the upper part of the still and another being exposed at such elevation in said still as to be covered by the normal liquid charge and be uncovered 95 whenever the charge falls abnormally low, whereby the difference in temperature between the liquid and gaseous media indicates whether or not the charge needs replenishing. 100

Signed at St. Louis, Missouri, this 7th day of March, 1917.

ARTHUR D. SMITH.
